BLADE GUARD FOR SKATES

Terrance G. Melnechenko, 28 Allenwood Crescent,
Willowdale, Ontario, Canada

Filed Apr. 3, 1974, Ser. No. 457,519

Term of patent 14 years

Int. Cl. D21—02

U.S. Cl. D34—14 B

FIG. 1 is a perspective view of a blade guard for skates showing my new design;
FIG. 2 is a side elevational view thereof;
FIG. 3 is a top plan view thereof;
FIG. 4 is a front elevational view thereof; and
FIG. 5 is a bottom plan view thereof.

I claim:
The ornamental design for a blade guard for skates,
as shown and described.
